UNITED STATES PATENT OFFICE.

FREDERIC H. MASON, OF SPOKANE, WASHINGTON.

FLUSHING DEVICE FOR WATER-CLOSETS OR OTHER FIXTURES.

SPECIFICATION forming part of Letters Patent No. 789,926, dated May 16, 1905.

Application filed March 11, 1903. Serial No. 147,261.

To all whom it may concern:

Be it known that I, FREDERIC H. MASON, a citizen of the United States, residing in Spokane, in the county of Spokane and State of 5 Washington, have invented a new and useful Improvement in Flushing Devices for Water-Closets or other Fixtures, of which the following is a specification.

My invention relates to flushing-tanks or 10 devices for water-closets and other fixtures.

The object of my invention is to provide an 15 automatic and noiseless flushing device for water-closets which will be simple, efficient, and durable in construction, in which the flushing-tank will remain normally empty and fill silently and rapidly and only to the required 20 height or depth, which will afford the customary afterwash, refill, or seal, and which will operate easily and with certainty under 25 high or low pressure, so that a very young child can operate it, and which can be applied to ordinary-sized supply-pipes of existing fixtures without change.

My invention consists in the means I employ to practically accomplish this important 30 object or result—that is to say, it consists, in connection with the bowl of a water-closet or other fixture, of a flushing-tank having a float 35 therein, a discharge-valve, an inlet-valve opening against and closing with the fluid-pressure and provided with a fluid pressure and flow 40 regulating device to cause the same to open and close easily and noiselessly without chattering, operating mechanism to close the discharge-valve and open the inlet-valve to cause 45 the flushing-tank, which remains normally empty, to fill, and a releasing device or trigger interposed in the operating mechanism and connected to and operated by the float to permit 50 the inlet-valve to automatically close when the water in the flushing-tank reaches the required height or depth. This releasing device or trigger preferably consists of a rotary member having a sliding movement with one 55 connecting part and a turning movement in respect to the other connecting part of the valve-operating mechanism in which it is interposed. The force exerted by the float is thus required only to operate the releasing device or trigger.

My invention also consists in the novel construction of parts and devices and in the novel combinations of parts and devices herein shown and described.

In the accompanying drawings, forming a 55 part of this specification, Figure 1 is a central vertical section of a flushing apparatus or device embodying my invention. Fig. 2 is a detail perspective view of the discharge-valve. Fig. 3 is a vertical section on line 3 3 of Fig. 60 1. Fig. 4 is a section on line 4 4 of Fig. 3. Figs. 5 and 6 are detail sections on lines 5 5 and 6 6, respectively, of Fig. 4.

In the drawings, A represents the bowl of a water-closet or other fixture; B, the flushing-tank; C, the float; C', the float-lever; D, the inlet-valve; D' D'', the valve-shell therefor; F, the discharge-valve, and F' the shell therefor.

G is a connection fitting or pipe connecting 70 the inlet-valve shell D', flushing-tank B, and the shell F' of the discharge-valve F.

H is the connection or pipe connecting the discharge-valve shell F' with the flushing-tank B and the overflow-pipe H' therein. 75

The connection or pipe G has an end g projecting into the flushing-tank B sufficiently above the bottom thereof to supply the required afterwash, refill, or seal to the bowl A after the flushing operation. This projecting 80 end g of the pipe G is furnished with small holes or openings g', through which the afterwash or refill water flows.

The inlet-valve D opens against the fluid-pressure and closes with it against the valve-seat d on the valve-shell D'. To cause the valve D to open and close easily and noiselessly and with certainty under high or low fluid-pressure, it is furnished with a fluid flow and pressure regulating device, consisting, preferably, of two pair of telescoping shells d' d'' and d' d'', the shells d' d'' each having coacting inlet-openings d' at their middle portions, one shell of each pair being stationary and connected to the valve-shell D' and the other 90 shell of each pair being movable and connected to the valve D. The stationary shell d' of the upper pair surrounds and incloses the valve-seat d, so that the water flowing through the valve-opening into the tank passes through 100

both of the upper pair of shells. The inner or movable shell d^2 of the upper pair is provided with openings or passages d^6 for the water. The movable shells d^2 d^4 are connected together by a connecting-rod d^7 , extending between the cross-bars d^8 and d^9 , which are attached to said shells d^2 and d^4 , respectively. The shell d^4 is slotted vertically to permit the bar d^9 to move up and down. The outer upper stationary shell d' is provided with a removable or screw-threaded head d^{10} , closing its lower end, and the lower stationary shell d^3 is removably attached to this head d^{10} by screw-threads. The lower end of the lower movable shell d^4 is closed by the removable or screw-threaded head d^{11} , having a small hole or passage d^{12} therein for the water. A spring d^{13} is preferably interposed between the lower end or head of the stationary shell d^3 and the movable shell d^4 . This spring will supplement the water or fluid pressure in closing the valve when the flushing-tank is filled and will counterpoise the weight of the water above the valve.

25 The valve D is provided with a metallic head D^3 for engagement with the device or lever which opens the valve. The discharge-valve F has an operating rod or stem f for closing it, which may be engaged by an arm α on the seat A' to close the discharge-valve. A spring f' , bearing against a collar f^2 on the stem f and a cross-bar f^3 , attached to the shell F', holds the valve F normally open and the seat A' slightly raised.

35 The valve D is preferably operated by a lever D^4 , having an antifriction wheel or roller D^5 to engage the metallic head D^3 on the valve, said lever being pivoted to a bracket or arm g^2 , secured to or made integral with the pipe or fitting G. This lever D^4 is preferably operated by an extension f^4 of the stem f of the discharge-valve F, said extension f^4 having a sliding connection with a hollow connecting-rod D^6 , which is pivotally connected with the lever D^4 . The connecting rod or extension f^4 is furnished with a pair of wings or projections f^5 , and there is interposed between the telescopic or sliding members f^4 and D^6 a releasing device or trigger M, which is connected with the float and operated thereby, which has the function when moved or operated by the float of permitting the two sliding or telescoping members f^4 D^6 of the inlet-valve-operating mechanism to slide or telescope in respect to each other, and thus automatically permit the inlet-valve to close when the tank fills to the required height. This trigger or releasing device may be of any suitable form or construction adapted to 55 perform this function; but it preferably consists, as illustrated in the drawings, of a rotatable hollow rod, thimble, or sleeve M, having slots or notches m in its front end M' to receive the wings or projections f^5 on the stem f^4 when said sleeve or thimble M is

slightly turned or moved by the float to bring said slots m into registry with the wings f^5 . The releasing device or trigger M has a rotatable and non-sliding connection with the sleeve or rod D^6 and a sliding or telescoping connection with the stem f^4 . This releasing device or sleeve M may thus be rotatably connected with the part D^6 by a set-screw m' , which fits in an annular channel m^2 in the part D^6 . The releasing device M is also provided with an internal flange or shoulder m^3 for the end of the rod or sleeve D^6 to abut against. The rotatable releasing device M is furnished with an operating-arm m^4 , connected by a link m^5 with the float-lever C', which is provided with collars C^2 C^3 for keeping the link in position on the lever. The float-lever C' is pivotally connected to the tank at C^3 . The shells or fittings D' D² G F' H and the coupling N to the fixture or bowl are all preferably removably connected together by the customary screw-threads and nipples, as illustrated in the drawings.

85 The valve-seat f^6 of the valve F may preferably be formed on a projecting screw-threaded boss g^3 on the fitting G. In operation the valve F is first closed by depression of the seat A', and at the same time the valve D is opened by the wings f^5 striking against the end of the releasing device M, and the valve D is thus held open until the tank B fills to the required height, when the float moves or trips the releasing device, and thus permits the two sliding members f^4 and D^6 of the inlet-valve-operating mechanism to 95 slide or telescope in respect to each other and the inlet-valve D to close under action of the fluid-pressure. The flushing-tank, which, as before stated, remains normally empty, is thus filled with water to the required depth 100 to properly flush the closet, which flushing action takes place automatically the instant the seat A' is released, so that the spring f' can open the discharge-valve F. The small discharge-openings g^7 in the fitting G supply 105 the required afterwash or refill to the closet-bowl after the flushing operation is completed.

110 The inlet-valve D is easily opened by a comparatively small weight on the seat A' by reason of the fluid pressure and flow regulating shells connected with the valve D, which also cause said valve to open and close steadily and without chattering. This also prevents any sudden gushing, gurgling, or hissing 115 movement. The connection or fitting G between the tank B and the inlet-valve shell and between the tank B and the discharge-valve shell F' is of comparatively large diameter or capacity, so that the water may flow 120 rapidly and quickly, fill the flushing-tank B, and suddenly discharge and properly flush the closet, and so that both of these actions or operations will be performed noiselessly 125 and without any disagreeable gurgling move- 130

ment. After the releasing device is turned or moved by the float and the inlet-valve thus permitted to automatically close as soon as the water is discharged from the flushing-
5 tank to flush the bowl and the float thus permitted to descend its weight and that of the float-lever and connecting-link will automatically return the releasing device into its normal position, so that the wings f^5 will at the
10 next operation of the closet again properly engage the end of the releasing device and through it operate to open the inlet-valve.

In my invention it will be observed that the flushing-tank and all connections remain normally completely empty, which adds to the durability of the parts and also specially adapts my improved closet or flushing device for use in exposed positions where there is liability to freezing.

20 It will be understood by those skilled in the art that while in the drawings I have illustrated my invention in a form wherein the inlet-valve is located close to the closet-bowl the inlet-valve may, if desired, be located at
25 a distance below the closet-bowl or below a normal freezing-point. It will also be understood by those skilled in the art that while in the drawings I have illustrated my invention as applied to a low-down flushing-
30 tank or one located close to the closet-bowl and the inlet-valve arranged in an upright or vertical position, which is the preferred construction to economize room for roughing in, these parts may be differently located and
35 arranged, if desired.

The lower stationary shell d^3 may preferably have a rubber or elastic pad d^{15} at its lower end, which may be compressed more or less by the cap d^{16} and adjusting-screw d^{17} to
40 vary the passage-way or space between itself and the surrounding movable shell d^4 , and thus regulate the freedom of movement of the shell d^4 and of the attached shell d^2 and valve D, as may be required, according to
45 the hydrant or street pressure of the water supply.

I claim—

1. In a water-closet the combination with the bowl, of a flushing-tank, a float and float-lever therein, a discharge-valve, an inlet-valve having a pair of fluid pressure and flow regulating shells furnished each with an inlet-opening at its middle side portion, one secured to the valve-shell and inclosing the valve-seat and the other connected with the valve and movable therewith, and a releasing device operated by the float to permit the inlet-valve to automatically close when the flushing-tank fills to the required height, substantially as
55 specified.

2. The combination with a flushing-tank, of a float, an inlet-valve opening against and closing with the fluid-pressure, a discharge-valve, operating mechanism for closing the

discharge-valve and opening the inlet-valve, 65 and a releasing device connected to and operated by the float to permit the inlet-valve to close when the tank fills to the required height, said releasing device being in a connection between the discharge-valve and inlet-valve, substantially as specified. 70

3. The combination with a flushing-tank, of a float, an inlet-valve opening against and closing with the fluid-pressure, a discharge-valve, operating mechanism for closing the 75 discharge-valve and opening the inlet-valve, having a two-part sliding or telescoping connection between said discharge-valve and said inlet-valve, and a rotatable releasing device connected to and operated by the float to permit the inlet-valve to close when the tank fills to the required height, said releasing device being in said two-part sliding or telescoping connection between the discharge-valve and the inlet-valve, substantially as specified. 80

4. The combination with a flushing-tank, of a float, an inlet-valve opening against and closing with the fluid-pressure, and provided with fluid pressure and flow regulating shells, a discharge-valve, operating mechanism for opening the inlet-valve having two sliding or telescoping members, and an interposed releasing device connected to and operated by the float, substantially as specified. 85

5. The combination with a flushing-tank, 95 of a float, an inlet-valve opening against and closing with the fluid-pressure, and provided with fluid pressure and flow regulating shells, a discharge-valve, operating mechanism for opening the inlet-valve having two sliding or telescoping members, and an interposed releasing device connected to and operated by the float, and mechanism for closing the discharge-valve, substantially as specified. 100

6. The combination with a flushing-tank, 105 of a float, an inlet-valve opening against and closing with the fluid-pressure, and provided with fluid pressure and flow regulating shells, a discharge-valve, operating mechanism for opening the inlet-valve having two sliding or telescoping members, and an interposed releasing device connected to and operated by the float, and mechanism for closing the discharge-valve comprising a hinged seat, an arm thereon, and a valve-stem, substantially 110 as specified.

7. The combination with a flushing-tank, of a float, an inlet-valve, a discharge-valve, two sliding or telescoping connecting members between the discharge-valve and inlet-valve, a rotatable releasing device connected with and operated by the float, one of said connecting members having wings and said releasing device having notches to receive said wings, substantially as specified. 115

8. The combination with a flushing-tank, of a float, an inlet-valve, a discharge-valve having a stem extension f^4 provided with wings

- f*⁵, a hollow connecting-rod D⁶ and a rotary releasing device M having slots or notches in its end to receive said wings, substantially as specified.
- 5 9. In a water-closet the combination with the bowl, of a flushing-tank, a float and float-lever therein, a discharge-valve, an inlet-valve having two pair of fluid pressure and flow regulating shells the upper pair furnished each 10 with an inlet-opening at its middle side portion, one secured to the valve-shell and inclosing the valve-seat and the other connected with the valve and movable therewith, and a releasing device operated by the float to permit 15 the inlet-valve to automatically close when the flushing-tank fills to the required height, substantially as specified.
- 10 10. The combination in a flushing device, of an inlet-valve provided with two pair of shells 20 forming fluid pressure and flow and pressure-closing compartments, a discharge - valve, mechanism for simultaneously closing the discharge-valve and opening the inlet-valve, fittings or shells connected to and uniting the 25 supply-pipe, flushing-tank and closet and inclosing said valves, and operating mechanism for said valves provided with a releasing device and a float and float-lever within the flushing-tank and connected to said releasing 30 device to permit the inlet-valve to automatically close when the flushing-tank has been filled to the required height, substantially as specified.
11. The combination with a normally empty 35 flushing-tank, of a discharge-valve, an inlet-valve, a float, mechanism for operating said valves and a releasing device connected to and operated by the float, said operating mechanism comprising two sliding or telescoping 40 parts which are permitted to slide or telescope in respect to each other by the tripping or moving of the releasing device, substantially as specified.
12. The combination with a flushing device, 45 of an inlet-valve provided with two pair of shells forming fluid pressure and flow and pressure-closing compartments, a discharge-valve, mechanism for simultaneously closing the discharge-valve and opening the inlet- 50 valve, fittings or shells connected to and uniting the supply-pipe, flushing-tank and closet and inclosing said valves, and operating mechanism for said valves provided with a releasing device and a float and float-lever within 55 the flushing-tank and connected to said releasing device to permit the inlet-valve to automatically close when the flushing-tank has been filled to the required height, said inlet-valve being provided with a fluid pressure and 60 flow regulating device, substantially as specified.
13. The combination with a flushing device, of an inlet-valve provided with two pair of shells forming fluid pressure and flow and
- pressure-closing compartments, a discharge- 65 valve, mechanism for simultaneously closing the discharge - valve and opening the inlet- valve, fittings or shells connected to and uniting the supply-pipe, flushing-tank and closet and inclosing said valves, and operating mech- 70 anism for said valves provided with a releasing device and a float and float-lever within the flushing-tank and connected to said releasing device to permit the inlet-valve to automatically close when the flushing - tank has 75 been filled to the required height, said inlet- valve being provided with a fluid pressure and flow regulating device, comprising two pair of telescoping shells, substantially as specified. 80
14. The combination in a flushing device, of an inlet-valve provided with two pair of shells forming fluid pressure and flow and pressure- 85 closing compartments, a discharge - valve, mechanism for simultaneously closing the discharge-valve and opening the inlet-valve, fittings or shells connected to and uniting the supply-pipe, flushing-tank and closet and inclosing said valves, and operating mechanism for said valves provided with a releasing de- 90 vice and a float and float-lever within the flushing-tank and connected to said releasing device to permit the inlet-valve to automatically close when the flushing-tank has been filled to the required height, said inlet-valve 95 being provided with a fluid pressure and flow regulating device, comprising two pair of telescoping shells, the upper pair of said telescoping shells one of which is movable with the valve having a spring interposed between them, substantially as specified. 100
15. In a water-closet the combination with the bowl, of a flushing-tank, a float and float-lever therein, a discharge - valve, an inlet- 105 valve having two pairs of fluid pressure and flow regulating shells, the upper pair furnished each with an inlet-opening at its middle side portion, one secured to the valve- shell and inclosing the valve-seat and the other connected with the valve and movable therewith, and a releasing device operated by the float to permit the inlet-valve to automatically close when the flushing-tank fills to the required height, one of the shells of the lower pair having an adjustable elastic pad to regulate the water-passage between itself and the other shell of said pair, substantially as specified. 110
16. The combination with a flushing-tank, of a float, an inlet - valve, a discharge-valve 115 having a stem extension f⁴ provided with wings f⁵, a hollow connecting-rod D⁶ and a rotary releasing device M having slots or notches in its end to receive said wings, the discharge-valve having a stem furnished with a spring for holding said valve normally open, substantially as specified. 120
17. The combination with a flushing-tank,

of a float, an inlet-valve, a discharge-valve having a stem extension f^4 provided with wings f^5 , a hollow connecting-rod D^6 and a rotary releasing device M having slots or notches in its end to receive said wings, the discharge-valve having a stem furnished with a spring for holding said valve normally open,

and seat and an arm on the seat engaging said valve-stem, substantially as specified.
